[57] ABSTRACT

A facsimile transceiver unit utilizing a drum wherein the drum gripper bar must be at a predetermined location when the drum is brought to a stop. Control circuitry stops the drum with the gripper bar within a certain window. An improved cam surface raises the gripper bar while at the same time rotating the drum so that the gripper bar is moved to a predetermined location within the window.

FIG. I

PRIOR ART

FIG. 2

**CONTROL
APPARATUS**

FIG. 4

FIG. 3

1
CAM

BACKGROUND OF THE INVENTION

This invention relates to positioning apparatus and, more particularly, to an improved cam configuration for imparting two directions of movement to a cooperating member.

In a facsimile transceiver unit utilizing a drum for conveying sheet material past a scanning station, a gripper bar which rotates with the drum is conventionally used for holding the sheet material to the drum. This gripper bar is normally biased toward the drum and is raised away from the drum by a cam surface when it is desired to either remove a sheet from the drum or place a sheet in contact with the drum. Such an arrangement is disclosed, for example, in U.S. Pat. No. 3,618,123. In a facsimile transceiver unit wherein documents are automatically fed onto and off the drum, such as that disclosed in copending application Ser. No. 253,721, filed May 16, 1972, and assigned to the assignee of the present invention now U.S. Pat. No. 3,790,159, it is necessary to stop the drum at a predetermined angular position so that the gripper bar is in the proper place to receive sheets. Illustrative control apparatus for performing this positioning function is disclosed in copending application Ser. No. 253,726, filed May 16, 1972 now abandoned, and assigned to the assignee of the present invention. The apparatus disclosed in the last-mentioned copending application will stop the drum so as to position the gripper bar within a certain angular window. However, for maximum sheet feeding reliability, it is desirable to have the drum stopped so that the gripper bar is at a particular location within that window.

SUMMARY OF THE INVENTION

In accordance with the principles of this invention, an improved cam surface configuration is provided for both raising the gripper bar and moving the drum so that the gripper bar is brought to a predetermined location within the angular window in which the gripper bar is initially stopped. The cam surface comprises two ramps forming a notch therebetween. When the cam surface is raised against the lower end of the gripper bar, this lower end is forced into the notch, thereby moving the gripper bar to the predetermined location as it is raised.

DESCRIPTION OF THE DRAWING

The foregoing will become more readily apparent upon reading the following description in conjunction with the drawing in which

FIG. 1 depicts illustrative prior art apparatus utilizing a cam to raise a gripper bar,

FIG. 2 depicts illustrative apparatus employing a cam embodying the principles of this invention wherein the cam is in an unengaged position,

FIG. 3 depicts the apparatus of FIG. 2 wherein the cam is in an engaged position, and

FIG. 4 is a perspective view of the illustrative cam shown in FIGS. 2 and 3.

DESCRIPTION OF THE ILLUSTRATIVE EMBODIMENT

Referring to FIG. 1, depicted therein is a portion of a prior art facsimile transceiver including drum 17 ro-

2

tating on shaft 10. Gripper bar 20 is utilized to hold sheet material against drum 17 and is described in detail in the aforementioned U.S. Pat. No. 3,618,123. Spring 23 biases gripper bar 20 against the surface of drum 17. Lever arm 25 is pivotably supported on shaft 27 and includes cam surface 28 at one end thereof. At the other end of lever arm 25 is surface 29. When surface 29 is moved down, surface 28 engages the lower end of gripper bar 20, thereby raising gripper bar 20 away from drum surface 17. Cam surface 28 is arranged to have a radial inclination so that when raised, drum 17 may be rotated in a clockwise direction and gripper bar 20 will ride up on cam surface 28. However, when drum 17 is at rest and cam surface 28 is raised, it will only raise gripper bar 20 in the angular position at which it is at rest, making no adjustment of this angular position.

Turning now to FIG. 2, depicted therein is the apparatus of FIG. 1 wherein an improved cam surface 30 embodying the principles of this invention is employed. When the illustrated apparatus is utilized in an automatic facsimile transceiver such as that disclosed in the aforementioned U.S. Pat. No. 3,790,159, it is necessary to stop drum 17 so that gripper bar 20 is near the topmost angular position. Control apparatus 50 for performing this function may illustratively be of the type disclosed in the aforementioned copending application Ser. No. 253,726. This illustrative control apparatus 50 stops the drum within an angular window of approximately 8° before the topmost position. In order to bring gripper bar 20 closer to the topmost position, cam surface 30 comprises ramp surfaces 31 and 32 which are inclined with respect to one another so that they form a notch at point 33. When the drum is positioned within the 8° angular window, the bottom edge of gripper bar 20 will lie above surface 32 as shown in FIG. 2. Therefore, when lever arm 25 is pivoted, the inclination of surface 32 will force gripper bar 20 so that its bottom end will be moved into the notch to point 33, thereby rotating drum 17 and consequently gripper bar 20 to the topmost position of the 8° angular window, as shown in FIG. 3.

FIG. 4 is a perspective view of lever arm 25 having improved cam surface 30 thereon.

Accordingly, there has been shown an improved cam surface for imparting both radial and angular motion to a cooperating member so as to force that member to a predetermined location within an angular window. Numerous other variations, modifications and adaptations of the present invention will be apparent to those skilled in the art and such as come within the spirit and scope of the appended claims are considered to be embraced by the present invention.

What is claimed is:

1. In facsimile apparatus, the combination comprising

a rotatable drum for conveying sheet material, a gripper bar extending through the surface of said drum and rotating with said drum, said gripper bar being biased toward the center of said drum for engaging an edge of said sheet material in fixed relationship to said drum surface, and

means for simultaneously moving said gripper bar radially outward from said drum and rotating said drum to a predetermined angular position including a cam movable from a first to a second position, said cam having a notched surface for engagement

with said gripper bar as said cam is moved from said first position to said second position, said first position being closer to the center of said drum and farther from the surface of said drum than said second position.

2. The combination of claim 1 wherein said cam surface includes a pair of ramp surfaces inclined with respect to one another so as to form a notch.
